CLAIM

The ornamental design for a patient monitor, as shown and described.

DESCRIPTION

1. Patient monitor

Fig. 1.1 is a front view of a patient monitor in accordance with the present design;

Fig. 1.2 is a back view thereof;

Fig. 1.3 is a left view thereof;

Fig. 1.4 is a right view thereof;

Fig. 1.5 is a top view thereof;

Fig. 1.6 is a bottom view thereof; and

Fig. 1.7 is a front right perspective view thereof.

The broken lines in Figs. 1.1-1.7 are included for the purpose of showing portions of the patient monitor that form no part of the claimed design.
